UNITED STATES PATENT OFFICE.

EDMUND BURKE KNAPP, OF SAN JACINTO, CALIFORNIA.

WHIP.

SPECIFICATION forming part of Letters Patent No. 369,015, dated August 30, 1887.

Application filed June 18, 1887. Serial No. 241,757. (No model.)

To all whom it may concern:

Be it known that I, EDMUND BURKE KNAPP, a citizen of the United States, residing at San Jacinto, in the county of San Diego and State 5 of California, have invented a new and useful Improvement in Whips, of which the following is a specification.

My invention relates to an improvement in whips; and it consists in the construction and 10 arrangement of the parts of the same, which will be more fully set forth hereinafter, and particularly pointed out in the claims.

The object of my invention is to provide a whip end to which the lash is adapted to be 15 attached, and is given a swivel movement to prevent the same from becoming twisted. I attain this object by the construction illustrated in the accompanying drawings, wherein like letters of reference indicate similar parts 20 in the several views, and in which—

Figure 1 is a perspective view of a portion of a whip with my improvement applied in connection therewith. Fig. 2 is a detail view 25 in perspective of the said whip end, on an enlarged scale. Fig. 3 is a longitudinal vertical section of the whip end.

A indicates a whip-stock, upon the end of which a metallic socket-ferrule, B, is mounted, at the upper end of which a circular groove, 30 b, is formed. This circular groove b is adapted to receive a metallic ring or annulus, and when said ring is seated in said groove it is flush with the outer surface of the socket B. This ring C has a loop, D, secured thereto, 35 which projects outwardly over the end of the socket B, and through its rigid connection with the said ring C insures a clearance by the lash secured thereto of the whip-stock.

The ring C and the loop D are adapted to be revolved around the socket B, the said ring C 40 having three movements in the groove b.

The lash is secured to the loop D, and through the movement of the said loop and the ring C, to which it is attached, the said lash also is given movement, and prevented by said 45 movement from becoming entangled with the end of the whip or being twisted around the same, as will be readily understood.

The novelty and utility of my improved whip being obviously apparent and appreciable, it is unnecessary to further enlarge upon the same herein. 50

Having thus described my invention, I claim—

1. As an improved article of manufacture, 55 the herein-described whip end, consisting of a socket having an annular groove formed therein, a ring adapted to have movement in said groove, and a rigid loop rigidly secured to the said ring and projecting outwardly from the 60 end of the said socket, substantially as described.

2. The combination, with the whip-stock, of the socket-ferrule B, having the annular groove b formed near the end thereof, the ring 65 C, mounted in said groove, and the rigid loop D, rigidly connected to said ring and having movement therewith, substantially as described.

In testimony that I claim the foregoing as 70 my own I have hereto affixed my signature in presence of two witnesses.

EDMUND BURKE KNAPP.
